Primary Examiner — Samantha Wood*Assistant Examiner* — Emily A Caven(74) *Attorney, Agent, or Firm* — Myers Wolin, LLC(57) **CLAIM**

The ornamental design for a pet toy, as shown and described.

DESCRIPTION

FIG. 1 is a front elevation view of a pet toy showing our new design;

FIG. 2 is a rear elevation view thereof;

FIG. 3 is a left side elevation view thereof;

FIG. 4 is a right side elevation view thereof;

FIG. 5 is a top view thereof;

FIG. 6 is a bottom view thereof;

FIG. 7 is a top, front, left perspective view thereof; and,

FIG. 8 is a section taken through line **8-8** of FIG. 1.

The dotted lines represent portions of the pet toy that form no part of the claimed design.
